STRAINING DEVICE FOR VACUUM DRYING APPARATUS

Augustinus Edvard Jonsson, Stockholm, Sweden

Application June 30, 1933, Serial No. 678,392
In Sweden August 31, 1932

11 Claims. (Cl. 183—52)

The present invention relates to a straining device in such vacuum drying apparatus as are provided with a rotating or oscillating drying drum, which by means of one or more strainers 5 communicates with a vacuum source, the said straining device being combined with a cleansing device, which during the rotary motions of the drying drum by the action of gravity is displaced in relation to the straining device. During this relative movement cleansing means (such as projections, teeth, needles or the like) cleanse the strainer openings.

Straining devices of the above mentioned kind are described in the U. S. Patent No. 1,748,955, 15 which discloses a cylindrical strainer provided with peripheral straining slots, into which extend cleansing teeth arranged on an eccentrically loaded holder pivotally journaled around the strainer and so arranged that during the rotary motion of the drying drum the cleansing teeth are displaced in said slots by reason of the fact that gravity tends to maintain said holder in a stable state of equilibrium. Owing to the character of the construction, the cleansing motion will proceed comparatively slowly as it takes place during a comparatively great part of a whole revolution of the drying drum. Further, no reversal of the direction of the cleansing will take place, until the direction of rotation of the 20 drying drum is reversed.

In a straining device according to the present invention a much quicker and more powerful cleansing action takes place and it is carried out during a small fraction of a revolution of the drying drum. Furthermore, the direction of the cleansing action during one revolution will be reversed, so that the cleansing members, during each complete revolution, will execute a cleansing motion back and forth across the 25 strainer.

The two above mentioned forms of a straining device according to the invention are by way of example illustrated on the accompanying drawings.

Fig. 1 is a section along line A—A in Fig. 2. Fig. 2 shows a plan view of a straining device according to the first mentioned form of the invention.

Fig. 3 is a section along line B—B in Fig. 4. Fig. 4 shows a plan view of a modification of the straining device from that shown in Figs. 1 and 2.

Fig. 5 illustrates diagrammatically the motions of the cleansing device according to Figs. 1—4 during the rotation of the drying drum.

Fig. 6 is a section along line C—C in Fig. 7.

Fig. 7 shows a plan view of a straining device according to the second above mentioned form of the invention.

Fig. 8 illustrates diagrammatically the motions of the cleansing device according to Figs. 6 and 7 during the rotation of the drying drum.

In the illustrated forms of the invention, the strainer is shown as a plane strainer, in Figs. 1 and 2 as a square plate with straight straining slots, in Figs. 3, 4, 6 and 7 as a circular disc provided with a great number of holes which, as illustrated, may suitably be arranged in rows. The straining device is attached to a gable wall of the drying drum and thus participates in the rotating motion of the latter. It may be arranged on the outside of a gable wall of the drying drum, and it may be enclosed in a special chamber that communicates with the source of 10 vacuum.

In Figs. 1 and 2, the strainer 1 is provided with a great number of parallel, straight straining slots 2. Into these extend projections or teeth 3 arranged on a holder 4, which constitutes a weight of a comparatively large mass. The number of teeth 3 corresponds to the number of slots 2. The holder or weight 4 is slidingly arranged along a straight bar 5 parallel with the straining slots. The bar 5 rests against the bosses 7 on the strainer and is attached by means of the bolts 6. To the bosses 7 are attached resilient stops 8, which limit the motions of the weight 4 along the bar 5 and take up the impacts. The part of the strainer provided with the straining slots 2 projects somewhat from the surrounding flange part of the strainer so that the cleansing teeth 3 without obstruction may be displaced along the whole length of the slots and somewhat or wholly outside of them in order to prevent impurities accumulating in the slots from being 15 packed together at the ends of the slots.

The modification shown in Figs. 3 and 4 differs from the foregoing form substantially with regard to the shape of the straining openings and the cleansing members. The straining openings are here shown as a large number of oblong holders 9 arranged in a plate 1^a that is attached to the frame 10 of the strainer. The plate 1^a is shown as being circular, but may also be rectangular. The holes 9 are suitably arranged in parallel rows. The cleansing members consist of resilient needles 11 attached in a fashion similar to a brush on the bottom side of the 20 sliding weight 4. When the weight 4 slides along the bar 5, the points of the needles 11 will 25 30 35 40 45 50 55

sweep across the surface of the strainer, and each needle will then alternately be elastically bent and again straightened out at the entrance into the strainer openings. Other parts in Figs. 3 and 4 are designated by the same numerals as corresponding parts in Figs. 1 and 2.

The displacements of the weight 4 along the bar 5 during the rotary motion of the drying drum are illustrated in Fig. 5, wherein a straining device has been diagrammatically shown in different positions during a revolution of the drum. 12 is the axis of rotation of the drum. 13 is the circular course along which the centre of the strainer 1 moves during the rotation of the drum. The strainer 1 and the bar 5 are so arranged that their parallel central lines will be tangents of said circular course 13. At the position of departure I in Fig. 5, the weight 4 is supposed to occupy the position furthest to the right and to be in contact with the corresponding stop 8. The bar 5 is now horizontal, but on the rotation of the drum in the direction of the arrow, the bar will begin to occupy an inclined position towards the horizontal plane. In a certain position II, the inclination has become so great that the action of gravity along the bar is equal to the friction. The weight 4 has now been brought to a starting position for a falling motion. On the continued rotation of the drum, said falling motion is quickly carried out and the weight slides over towards the other stop 8, during which motion the teeth or needles effect a thorough cleansing of the strainer. In the position III the bar 5 is vertical and the falling motion has been completed.

In the position IV diametrically opposite to position II, the inclination of the bar 5 is again such that a new falling motion may begin. The weight will then move in a reversed direction in relation to the strainer. In position V the bar 5 is again vertical, but the weight 4 is now again at the lower end of the bar, and a new falling motion has been completed. The strainer is thereupon carried back to the position of departure I without further motion of the cleansing members. Thus, the weight has during a revolution of the drum completed a motion back and forth along the bar and consequently cleansed the strainer twice and in opposite directions. On the reversal of direction of rotation of the drum, the falling motions of the weight will occur in the same way.

According to the form illustrated in Figs. 6 and 7, the holder carrying the cleansing members is in the form of a weight-loaded arm 14; pivotally journalled on a gable wall of the drying drum about the pin 15. The strainer and the cleansing members are in this case shown in a form similar to that illustrated in Figs. 3 and 4. The pivot pin 15 should be arranged between the centre of the strainer 21 and the axis of rotation of the drum. The free end of the arm 14 should suitably constitute a weight of a comparatively large mass. On the side of the weight 16, turned towards the strainer, the cleansing members are attached. Two stops 17 and 18 are attached on the gable wall of the drum in order to limit the motions of the arm 14.

Said motions during a revolution of the drum are diagrammatically illustrated in Fig. 8. 19 is the axis of rotation of the drum, and 20 is the circular course along which the centre of the strainer 21 moves during the rotation of the drum. In the position of departure I, the arm 14 is supposed to rest against one of the stops

17. On the rotation of the drum in the direction of the arrow, the arm 14 will at first more and more approach a vertical position. In position II this is supposed to have happened. The arm 14 now occupies a position of unstable equilibrium. After some further motion of the drum, the arm will fall down on account of the action of gravity, and the cleansing is quickly carried out. The arm 14 will thereupon at first rest against the other stop 18, as indicated by dot and dash lines at position II. On the continued rotation of the drum the arm 14 will again approach a new vertical position, which has been reached in position III. The weight-loaded end now hangs downwards, and the arm has left the contact with the stop 18 and has now occupied a position of stable equilibrium, in which gravity strives to maintain it.

During the next following period a relative motion will therefor occur between the arm 14 and the strainer in an opposite direction to the motion just described, although slower. During this relative motion, the strainer is cleansed once more but in the opposite direction. In position IV, diametrically opposite to position I, the arm 14 hangs vertically downwards along the central line of the strainer. In position V, the arm 14 has passed over the strainer and finished the second cleansing operation. It is realized that during the continued rotation of the drum contact will finally occur between the stop 17 and the arm 14, which happens in position VI, whereupon the position I will again be gradually reached without any further relative motion between the cleansing device and the strainer. On the rotation of the drum in the opposite direction, the operation is carried out in the same way, but the arm 14 will then be brought to a position of unstable equilibrium by means of the other stop 18.

According to the invention, the cleansing member is arranged on a holder loaded by a weight, which is guided and arranged in such a way that during the rotary motion of the drying drum it is periodically brought into starting positions for a free falling motion, during which motion the cleansing action is quickly accomplished. According to one form of the invention, the said weight is guided along a straight line by means of one or more straight bars so arranged that they, during the rotary motion of the drying drum, will occupy inclined positions towards the horizontal plane, thereby causing the falling motion of the said weight. According to another form of the invention, said weight is arranged on a pivoting arm, which is so journalled and so guided by stops arranged on the drying drum that the weight during the rotary motion of the drum will be brought into a state of unstable equilibrium, from which, during the continued rotation of the drum, it will carry out a quick falling motion with accompanying cleansing operation.

The invention is not limited to the illustrated forms. The straining and cleansing device may be modified in different ways without departing from the spirit of the invention.

Having now particularly described the nature of my invention and the manner of its operation what I claim is:

1. A device of the character described, comprising in combination, a rotatable support, a straining device mounted to take part in the rotary motion of said support, the surface of said straining device being provided with strain-

- ing openings, a weight-loaded cleansing device provided with cleansing members adapted to enter said straining openings, means for guiding said weight-loaded cleansing device during the 5 rotation of said support so as to bring it to a starting position for a falling motion, during which the cleansing operation takes place by displacement of the cleansing members in the straining openings.
- 10 2. A device of the character described, comprising in combination, a rotatable support, a straining device mounted to take part in the rotary motion of said support, the surface of said straining device being provided with straining openings, a weight-loaded cleansing device provided with cleansing members adapted to enter said straining openings, means for guiding said weight-loaded cleansing device during the 15 rotation of said support so as to bring it to a starting position for a falling motion, during which the cleansing operation takes place by displacement of the cleansing members in the straining openings, said weight-loaded cleansing device having means for guiding it in a straight 20 line along the surface of the strainer.
- 25 3. A device of the character described, comprising in combination, a rotatable support, a straining device mounted to take part in the rotary motion of said support, the surface of said straining device being provided with straining openings, a weight-loaded cleansing device provided with cleansing members adapted to enter said straining 30 openings, means for guiding said weight-loaded cleansing device during the rotation of said support so as to bring it to a starting position for a falling motion, during which the cleansing operation takes place by displacement of the cleansing 35 members in the straining openings, said weight-loaded cleansing device being arranged as a pivot arm so adapted that said guiding means during the rotation of the support will bring it into an unstable position of equilibrium, which will be the 40 starting point of said falling motion.
- 40 4. A device according to claim 3, and wherein 45 the pivot of said pivot arm is arranged between the centre of the strainer and the axis of rotation of said support.
5. A device according to claim 1, and wherein the strainer is formed as a plate with straight parallel straining slots.
6. A device according to claim 1, and wherein the strainer is formed as a plate provided with a great number of holes arranged in rows, and wherein the cleansing members consist of resilient needles.
7. A device according to claim 2, and having stops for limiting the motion of the weight-loaded 10 cleansing device.
8. A device according to claim 2, and having resilient stops for limiting the motion of the weight-loaded cleansing device.
9. A device according to claim 3, and wherein 15 said guiding means consist of stops attached to said support to limit the swinging motions of said pivot arm.
10. A device of the character described, comprising in combination, a rotatable support, a 20 straining device mounted to take part in the rotary motion of said support, the surface of said straining device, being provided with straining openings, a weight-loaded cleansing device provided with cleansing members adapted to enter said straining 25 openings, means for guiding said weight-loaded cleansing device during the rotation of said support so as to bring it to a starting position for a falling motion, during which the cleansing operation takes place by displacement of the cleansing 30 members in the straining openings, said weight-loaded cleansing device comprising a pivot arm so adapted that said guiding means during the rotation of the support will bring it into an unstable position of equilibrium, which will be the 35 starting point of said falling motion, said guiding means consisting of stops attached to said support to limit the swinging motions of said pivot arm and so arranged that the weight-loaded pivot arm will during the rotation of said support be directed 40 outwards from the axis of said support.
11. A device according to claim 1 and wherein the straining openings consist of straight slots with open ends.

AUGUSTINUS EDVARD JONSSON.
